MEANS AND METHOD OF APPLYING COILED LAYERS OF RAFFIA TO THE BOTTOM OF BOWLS

Israel Bloom, New York, and Jess Abrams, East Rockaway, N. Y., assignors to Conelstan Corporation, New York, N. Y., a corporation of New York

Application January 18, 1952, Serial No. 267,101

2 Claims. (Cl. 154—1.7)

1

The invention herein disclosed relates to the manufacture of raffia covered bowls.

These are produced usually by adhering the end of a strip of raffia to the bottom of the bowl and then winding the strip spirally from that point across the bottom and then over the sides of the bowl.

Difficulty is frequently experienced in attaching the raffia and getting the coil started on the bottom of the bowl.

Objects of the present invention are to provide means for starting the coil separate from the bowl and which can then be used to apply and secure the coiled strip to the bottom of the bowl.

It is a further purpose of the invention to provide such means in a simple, practical and inexpensive form which can be easily used without any previous experience or training.

Other desirable objects attained by the invention are set forth or will appear in the course of the following specification.

The drawing accompanying and forming part of the specification illustrates an embodiment of the invention and the new mode of operation which it makes possible. Structure, however, may be modified and changed as regards this illustration, all within the true intent and scope of the invention as hereinafter defined and claimed.

Fig. 1 in the drawing is a perspective view of the disc for starting the coiling action;

Fig. 2 is a similar view showing the end of a strip of raffia inserted through a holding opening in the disc and the first turn taken about the post at the center of the disc;

Fig. 3 is a plan view showing how successive coils are wound over the face of the disc;

Fig. 4 is a cross sectional view of the disc as on substantially the plane of line 4—4 of Fig. 1;

Fig. 5 is a bottom plan view of a bowl with the disc on which a layer of the raffia has been coiled, applied;

Fig. 6 is a side elevation of the bowl with the disc left in place and the strip wound up over the sides of the bowl;

Fig. 7 is a perspective view of the completed bowl.

In this invention a layer of raffia is first coiled on a disc 10 and then this layer is secured as a unit to the adhesively coated bottom of the bowl 11.

In starting, the end of the raffia is temporarily secured near the center of the disc by inserting

2

it through a hole 12 of a size to snugly receive the end of the raffia strip 13.

Adjoining the retaining hole and located substantially at the center of the disc, is a small pin or post 14 of about the same diameter as the raffia and projecting from the face of the disc a distance approximately the same or less than the diameter of the raffia.

Figs. 2 and 3 show how with the end of the raffia caught in the opening 12, successive coils may be wound over the face of the disc, this being easily accomplished by relatively rotating the disc while holding the raffia under light tension and pressed flat against the face of the disc.

After a layer of coiled raffia is completed as in Fig. 3, the entire layer may be applied as a unit to the bottom of the bowl, after this surface of the bowl has been coated with suitable adhesive, 20 by simply reversing the disc and pressing the layer firmly over the coated surface, as in Fig. 5.

After allowing sufficient time for the adhesive to set, the disc may be removed by simply lifting it away from the adhesively attached coiled 25 layer.

In removing the disc care should be observed to prevent the disc from pulling the end of the raffia in the hole 12 away from the attached layer. This can be assured by pressing inward 30 on the end exposed in the hole 12 as the disc is lifted away from the attached layer, using a pick to force the end back out of the hole.

Fig. 6 shows how the winding may be continued across the bottom and up the sides of 35 the bowl while the disc remains in place, held to some extent by the end of the raffia engaged in the retaining hole. This is not necessary however, as the disc may be removed as soon as the layer coiled thereon has become firmly attached to the bowl.

The winding or starting disc may be made of plastic or other such material, molded all in one piece, substantially as indicated in Fig. 4.

The device is simple, practical and inexpensive 45 and provides a means by which anyone may quickly and easily form a preliminary coiled layer of raffia and then attach it to the bowl or other structure and which can then be removed, leaving the coiled layer firmly secured in place and providing the beginning of the complete raffia covering.

The center winding post 14 may be of substantially the same size as the raffia but ordinarily should not project from the face of the disc beyond the diameter of the raffia, so as not to pre-

vent the raffia from being pressed firmly against the bottom of the bowl.

What is claimed is:

1. A device for forming and applying a coiled layer of raffia to the bottom of a bowl, comprising a flat disc having an opening near the center of the same, of a size to receive the end of a strip of raffia, and a post of about the same diameter as the raffia, adjoining said opening and located substantially at the center of the disc and projecting from the face of the disc a distance approximating the diameter of the raffia and about which a length of raffia, caught at the end in the opening, may be wound in an ever increasing spiral in a single flat layer on the face of the disc and which may be applied by the disc in a single layer over the bottom of the bowl.

2. The method herein disclosed of applying a starting layer of coiled raffia to the bottom of a bowl which has been coated with adhesive, and comprising providing a disc with a hole near the

center and a projecting post adjoining the hole and substantially at the center of the disc, inserting the end of a strip of raffia through said hole and then winding the strip about said post in an ever increasing spiral layer over the face of the disc and then applying the complete layer to the adhesively coated bottom surface of the bowl by pressing the layer covered face of the disc against the adhesively coated bottom of the bowl and thereafter lifting the disc away from the applied layer and in so doing freeing the hole in the disc from the end of the raffia.
